UNITED STATES PATENT OFFICE.

EDMUND IRA RICHARDS, OF BROOKLYN, NEW YORK.

DESIGN FOR A SPOON.

SPECIFICATION forming part of Design No. 21,868, dated September 27, 1892.

Application filed March 26, 1892. Serial No. 426,607. Term of patent 7 years.

To all whom it may concern:

Be it known that I, EDMUND IRA RICHARDS, a citizen of the United States, residing at Brooklyn, in the county of Kings and State 5 of New York, have invented and produced a new and original Design for Spoons, of which the following is a specification.

Reference is to be had to the accompanying drawing, forming a part of this specification, 10 in which the figure represents a plan view of a spoon having my new design embodied in the handle thereof.

The essential feature of my design is the configuration and ornamentation of the upper end of the handle of the spoon, such configuration and ornamentation comprising a 15 shield-shaped extremity, the lower point of the shield passing into and coalescing with the handle.

A is the handle of the spoon, and A' the 20 bowl thereof. Within the shield-like figure 12 is a semicircular figure 10, approximating in shape a letter C, and within the semicircular figure 10 is the rustic figure 11, the said rustic figure being formed with a single perpendicular and three horizontal members, the members being grouped in such a manner as to approximate or simulate the letter E. 25

I claim—

The design for a spoon herein shown and de- 30 scribed.

EDMUND IRA RICHARDS.
